(57) CLAIM

The ornamental design for a hook tape screening repair patch, as shown and described.

DESCRIPTION

FIG. 1 is a perspective view of the non-engagement side of hook tape screening repair patch.

FIG. 2 is a perspective view of the engagement side of hook tape screening repair patch; and,

FIG. 3 is an enlarged fragmentary elevational view of the engagement element portion of the hook tape screening repair patch, taken at line 3—3 of FIG. 2 for clarity of disclosure.
